UNITED STATES PATENT OFFICE.

FREDERICK HACKMANN, OF CHICAGO, ILLINOIS,

TRACK-ALIGNING JACK.

Application filed January 25, 1924. Serial No. 688,395.

To all whom it may concern:

Be it known that I, FREDERICK HACKMANN, a citizen of the United States, and a resident of the city of Chicago, in the county of Cook and State of Illinois, have invented certain new and useful Improvements in a Track-Aligning Jack; and I hereby declare that the following is a full, clear, and exact description of the same, reference being had to the accompanying drawings, and to the numerals of reference marked thereon, which form a part of this specification.

This invention relates to a rail aligning jack which is adapted for engaging the lower flange of the rail for shifting the same laterally.

The invention comprises the novel structure and combinations hereinafter described and more particularly pointed out and defined in the appended claims.

In the accompanying drawings which illustrate a preferred embodiment of this invention and in which similar reference numerals refer to similar features in the different views:

Figure 1 is a sectional view through a railroad track illustrating a pair of my improved rail aligning jacks, in elevation and in operation.

Figure 2 is an enlarged section through the jack taken substantially upon the line 2—2 of Figure 1, showing parts in elevation.

Figure 3 is an enlarged fragmentary vertical sectional view with parts in elevation.

Figure 4 is an elevational view of a modified form of the rail engaging element.

Referring to the drawings which illustrate one embodiment of this invention, the reference numeral 1 indicates the base of the jack from which a hollow standard or guide rises. The guide is shown as of hollow rectangular form having an opening 3 (Fig. 2) in its front face. A rack bar 4 is slidably mounted in the guide 2. The upper end of the rack bar is provided with ratchet teeth 5 adapted for engagement by a pawl (not shown) upon an operating lever 6 pivoted upon the standard. The operation of such a rack bar by a lever is well known and needs not be specifically illustrated.

The lower end of the rack bar is provided with a forwardly extending lug 7 upon which the rail engaging device is removably

supported. Several rail engaging devices are illustrated. The preferred form consists of a shoe or supporting member 8 having a downwardly inclined outer end or face 9 and a mortise or socket in its inner end 60 which fits the lug 7 as shown in Figure 3. A rail engaging element 10 is pivoted upon the upper outer corner of the shoe 8. The upper side of this element is serrated for engaging against the lateral edge of the 65 lower flange of the rail. This rail engaging element is in the form of a lever in action as its lower end is adapted to bite in the ground, while the rail is engaged intermediate its ends and power is applied 70 to its upper end for elevating the same. It is obvious that this element 10 may be made as long as desired so that right length of throw or adjustment may be effected.

In Figure 4 I have shown the second form 75 of rail engaging device. The same consists of a rail engaging element having a horizontal portion 11 provided with a socket for engaging over the lug 7, and a downwardly inclined outer portion 12 which extends below the horizontal portion, and which is serrated upon its upper surface for engaging the rail.

In use, the jack is positioned adjacent the rail to be shifted or aligned, with the rail 85 engaging element under the rail, as shown in Figure 1. Then by operating the handle 6, the rack bar may be elevated whereby the lateral component of force directed against the rail by the inclined face of the rail engaging element will shift the rail laterally 90 as is apparent.

It will be appreciated that the jack is simple in construction and efficient in operation, the removable feature of the rail engaging element allows another of greater or less throw to be substituted or a new element substituted if the old one wears out.

I am aware that many changes may be made, and numerous details of construction 100 may be varied through a wide range without departing from the principles of this invention, and I therefore do not purpose limiting the patent granted hereon, otherwise than necessitated by the prior art.

I claim as my invention:

1. In a rail aligning jack, a base, a hollow vertical guide having its front side partially open rising from said base, a rack bar slidably mounted in said guide and having a 110

lug projecting through the open side thereof, a support having a downwardly sloping end removably secured upon said lug, a rail engaging element pivoted to said support and means for operating said rack bar.

2. In a rail aligning jack, a base, a hollow vertical guide rising from said base, a rack bar slidably mounted in said guide and having a horizontal lug upon its lower end, a supporting member removably secured upon said lug, a rail engaging element pivoted to

said supporting member, and means for operating said rack bar.

3. In a rail aligning jack, a base, a hollow vertical guide rising from said base, a rack bar slidably mounted in said guide and having a lug upon its lower end and a member having an inclined face and a socket adapted for detachable engagement with said lug.

In testimony whereof I have hereunto subscribed my name.

FREDERICK HACKMANN.
